UNITED STATES PATENT OFFICE.

ALFRED S. POWELL, OF NEW YORK, N. Y., ASSIGNOR TO MAURICE STRANSKY, OF MOUNT VERNON, NEW YORK.

SEMI-INDIRECT-LIGHTING DEVICE.

1,203,046.

Specification of Letters Patent. Patented Oct. 31, 1916.

Application filed June 12, 1916. Serial No. 103,143.

To all whom it may concern:

Be it known that I, ALFRED S. POWELL, a citizen of the United States, residing at New York, in the county of Kings and State 5 of New York, have invented certain new and useful Improvements in Semi-Indirect-Lighting Devices, of which the following is a full, clear, and exact description.

This invention relates to illuminating devices, and its object is to provide simple and effective means, capable of being manufactured at low cost, for supporting a light-diffusing "bowl" or globe around an electric lamp or other source of light.

To this and other ends the invention consists in the novel features and combinations hereinafter described.

One form of the invention is illustrated in the accompanying drawing, which shows the 20 complete device in perspective.

In the present form of the invention the source of light is an incandescent electric lamp 10, hanging from the usual socket 11. The latter carries a reflector-support comprising a split ring 12 encircling the socket and removably clamped thereon by a binding screw 13, and a gallery 14 provided with the usual radial screws, as 15, to releasably engage an outwardly extending flange on the 25 flat, downwardly flaring reflector 16, which latter is preferably made of white or opal glass.

The translucent ground glass diffusing bowl 17, preferably white or opal in color, 30 has at its top an outwardly extending flange 18. The latter rests on the inwardly extending flange 19 of a spring metal ring or annulus 20. With the exception of its flange 18, said bowl is smaller in diameter than the 35 ring 18 and flange 20, so that it can be passed down through the ring to bring the two flanges into engagement. The ring is preferably slightly smaller in diameter than the reflector 16.

The ring 20 is suspended by means of short legs or hangers 21, of metal, riveted to the ring at their lower ends and having their upper ends bent to form inwardly disposed hooks 22, which engage the edge of the flaring reflector 16, thereby suspending the ring 45 and bowl from said edge. The hangers are 50 preferably long enough to leave ample ven-

tilating space between the bowl and the reflector, thereby protecting these parts from possible breakage by the intense heat of a 55 high power lamp. The space also provides an unrestricted outlet for reflected light, far enough above the eye-level to avoid being unpleasant, while the rays which would strike the eyes are intercepted and diffused by the 60 bowl. The advantages of semi-indirect lighting are thus obtained, as regards agreeableness to the eye and avoidance of heavy shadows, with less absorption of light than occurs when the diffusing globe entirely in- 65 closes the lamp.

The bowl is readily removed by first springing the hangers outwardly to disengage their hooks 22 from the edge of the reflector. The bowl can then be lifted out of 70 the supporting annulus 20, and the lamp unscrewed from the socket. Re-assembly of the parts is of course equally simple and easy. In the form shown, no lateral pressure can be exerted on the edge of the bowl by the 75 supporting annulus, since there are no screws which a careless user might turn up too tightly. The spring pressure of the hangers on the reflector-edge can also be light enough to avoid danger of breakage, though firm 80 enough to support the bowl with security.

What I claim is:

A semi-indirect lighting device, comprising a socket to hold a lamp in depending position, a flat downwardly flaring reflector 85 supported on said socket, a translucent, upwardly open diffusing bowl below said reflector to receive a lamp suspended from said socket, and having an outwardly extending flange at its top, a supporting annulus encircling the top of the bowl and having 90 means underlying the said flange to support the bowl, and a plurality of hangers attached to the annulus at their lower ends and having their upper ends hooked to engage the 95 edge of said reflector to suspend the annulus and bowl therefrom and leave a ventilating and light-transmitting opening between the bowl and the reflector, substantially as and for the purpose set forth.

In testimony whereof I hereunto affix my signature.

ALFRED S. POWELL.
